UNITED STATES PATENT OFFICE.

EMIL W. SCHROEDER, OF ERIE, PENNSYLVANIA, ASSIGNOR OF ONE-THIRD TO CHARLES E. BLOOM, OF ERIE, PENNSYLVANIA.

EMERGENCY-VALVE.

1,325,334.

Specification of Letters Patent. Patented Dec. 16, 1919.

Application filed August 10, 1918. Serial No. 249,269.

To all whom it may concern:

Be it known that I, EMIL W. SCHROEDER, a citizen of the United States, and resident of Erie, in the county of Erie and State of Pennsylvania, have invented certain new and useful Improvements in Emergency-Valves, of which the following is a specification.

This invention relates to the class of valves, and more particularly to an improvement whereby the valve head may be held upon its seat by auxiliary means, permitting the main valve stem to be removed for the purpose of renewing the gasket or packing, 15 a broken stem or yoke.

A further object of the invention is to permit the valve to be held on its seat, thereby permitting the renewal of broken or defective parts, without the necessity of cutting out the line, or in the case of a steam power system as used on battle ships, power plants, and the like, to obviate the necessity of putting out the furnace, reducing the steam pressure to zero and then repairing 20 the line, as would require that the fires be remade and the steam pressure brought to normal with considerable expenditure and difficulty, while the present device permits the saving of time and expense, the repair 25 being capable of being made in a very short space of time and with considerable facility.

A further object of the invention is to provide an improved valve having a valve head capable of detachment from the stem 30 while the valve casing and the valve head are provided with coöperative means in the form of auxiliary stems adapted to hold the valve head to its seat, independently of the main valve stem, whereby the latter can be 35 removed for repair purposes, as specified.

With the above and other objects in view, as will appear as the description proceeds, the invention comprises the various novel features of construction and arrangement of 40 parts which will be more fully described herein and set forth with particularity in the claims appended hereto.

Reference is had to the accompanying drawings forming a part of this application, in which like reference characters indicate the corresponding parts throughout the several views, in which

Figure 1 is a vertical sectional view of a globe valve equipped in accordance with the invention, and

Fig. 2 is a horizontal sectional view taken across the valve casing on the line 2—2 of Fig. 1.

Referring to the drawings in detail, the numeral 10 designates the casing of the 60 valve, illustrated in the form of a globe valve, although it is to be understood that the device may be applied to gate valves, or other types of valves. This casing is shown provided with the inlet 11 and outlet 12, the 65 same having the sealed closure plate or bonnet 13, through which the valve stem 14 operates. The casing is provided with a seat 15 against which a valve head 16 is designed to seat, the stem being designed to 70 be actuated through the medium of a handle or wheel 17, there being a suitable packing gland or joint 18 for the valve stem where it operates through the bonnet, so as to prevent the escape of steam or other fluid, while 75 said stem is threaded through the yoke or bar 19, forming a two-point guide, as is usual in valves of this type.

In order to detachably connect the valve stem to the valve head, so as to permit the 80 latter to be raised assisted by the action of the fluid pressure from the bottom entering through the inlet 11, the valve head is provided with a globular socket 20 communicating with its upper portion, and the lower 85 end of the valve stem is provided with a reduced portion having secured at diametrically opposite sides thereof outwardly bowed springs 21, the same being in the form of sections of spring metal in strip form with 90 their ends seated in and anchored to the valve stem, as shown at 22. By this means, engagement may be had with the valve head for the purpose of attaching the valve head to the stem and permitting the same to be 95 raised and lowered in the opening and closing of the valve, in the usual manner.

The valve head 16 is also provided with a beveled edge portion having diametrically opposed arcuate grooves 23 therein, and the 100 adjacent portions of the casing 10 are formed with lugs 24 corresponding to the lug 25 for the main valve stem. The main valve stem is threaded for operation in the usual manner, and operating through the 105 lugs 24 are stems 26, which may be termed auxiliary stems, since the lower ends thereof are designed to coöperate with the recesses or grooves 23, so as to hold the valve 16 on its seat independently of the main 110

valve stem. The auxiliary stems are threaded at their inner ends and operate through the packing glands or bonnets 27 having lugs 28 for attachment and corresponding 5 to the yoke 19.

Thus, it will be seen that by inwardly screwing the auxiliary stems, the main valve stem may be disengaged by reason of its detachable engagement with the valve head 16, 10 thereby permitting parts to be repaired or renewed, without the necessity of shutting off the power. The device is designed to save time and labor in the boiler room or engine room of ships, and also other steam 15 power plants, in connection with globe valves, gate valves, or other types of valves, and especially in the case of an accident such as the blowout of a gasket of the valve or a boiler stop valve, thereby permitting 20 the renewal or repair of the parts, in a very short time, without the necessity of drawing fires, cooling the boiler down and waiting until the pressure is off and then remaking the fires and getting up pressure after the 25 repairs are made, such as would require a considerable length of time. The device is especially adapted to globe valves as generally used upon marine engines in connection with ships of all sorts, or other steam 30 power plants. The device is equally well adapted for feed valves, top and bottom blow-down valves, or valves intended for various other uses, as well as sea valves or cocks in sea pressure so that it will not be 35 necessary to place a ship in dry dock to repair the same, if anything goes wrong with the sea valves.

From the foregoing description taken in connection with the accompanying drawings, 40 it is thought that a clear and comprehensive understanding of the construction, operation, and advantages of my invention may be had, and while I have shown and described the device as embodying a specific 45 structure, I desire that it be understood that such changes may be made in said structure, as do not depart from the spirit and scope of the invention as claimed.

Having thus described my invention, what

I claim as new and desire to secure by Letters 50 Patent, is:

1. A valve comprising a casing having a seat and a valve head coöperating therewith, an inlet and an outlet, a valve stem operating through said casing and detachably engaging said head, diametrically oppositely disposed auxiliary stems engaged through the casing at either side of the main valve stem and coöperating with the valve head to hold the same seated independently of the main valve stem, and resilient means detachably fastening the valve head to the valve stem.

2. A valve comprising a casing having a seat and a valve head coöperating therewith, an inlet and an outlet, a valve stem operating through said casing and detachably engaging said head and diametrically oppositely disposed auxiliary stems engaged through the casing at either side of the main valve stem and coöperating with the valve head to hold the same seated independently of the main valve stem, said valve head having a globular socket, and springs carried by the valve stem detachably engaging said socket.

3. In a valve of the class described, a casing having an inlet and an outlet, a valve seat and a valve head therein having a globular socket, a valve stem for said valve having a reduced lower portion, springs secured upon opposite sides of the reduced lower portion of said valve stem and bulging outwardly to detachably engage said socket, a bonnet and a yoke through which said valve stem operates, lugs projecting inwardly from the casing at diametrically opposite points, packing glands in the casing, and auxiliary stems operating through said packing glands and passing through said lugs, said valve head having opposed recesses coöperating with the ends of said auxiliary stems, whereby said valve head can be held seated independently of the main valve stem.

In testimony whereof, I affix my signature hereto.

EMIL W. SCHROEDER.
